UNITED STATES PATENT OFFICE.

HARRY P. CROOK, JR., OF BALTIMORE, MARYLAND.

GAME.

Application filed January 10, 1921. Serial No. 436,104.

To all whom it may concern:

Be it known that I, HARRY P. CROOK, Jr., a citizen of the United States of America, residing in the city of Baltimore, State of Maryland, have invented certain new and useful Improvements in Games, of which the following is a specification.

The present invention relates to a game or toy in the nature of a miniature electric railroad, the object of which is to demonstrate, exercise or cultivate the skill of the players as applied to stopping the trains by each particular player at his individual station.

15 The game consists of an electrically driven train running on a continuous or endless track with stations or stopping places each to be presided over by one of the players, each of whom exercises and 20 attempts to demonstrate his skill by stopping the train at his station.

In the form shown, each station or stopping place is provided with separate mechanism which is duplicated at each station, the 25 mechanism in connection with each station being referred to herein as a unit. Each unit is to be operated by a player who attempts to stop the train within his particular block or at the station corresponding to 30 his unit. Each such unit in the form of the invention shown includes a stop or detent which is capable of being moved into the path of the train. The detent in each unit is within the control of the corresponding player and may, if the apparatus comprising his unit is properly operated by him, be moved by him into the path of the train to be actuated by the train as hereinafter 35 described. The detent is, however, normally withdrawn and to enable the player to cause it to be interposed in the path of the train so that the train will come in contact with it in passing, requires the exercise of a considerable degree of skill on the 40 part of the player.

45 This detent in turn controls a switch or other means for stopping the train and contact of the train with the detent serves to actuate the switch or other mechanism to stop the train. The stopping is not necessarily positive. The switch in each unit

thus described serves to break the train circuit at a definite position of the train which stops the train opposite the corresponding station with a fair degree of uniformity. 55

Preferably and as shown, each player unit also includes a signal which shows one color as red when the detent is in the path of the train and another color as green when it is withdrawn; it also shows red when the train 60 is stopped at the corresponding station.

Preferably and as shown, each unit also includes means for controlling the lights in the corresponding station so that when the train is stopped at any particular station 65 a particularly bright lighting effect will be produced at that station.

In the accompanying drawing, I have illustrated a game embodying my invention in the preferred form. In the drawing 70

Figure 1 is a diagrammatic illustration including the track, the main or train circuit, the player units and the wiring, etc., incident to several of these units, the same being reduced and broken away for convenience in illustration. 75

Figure 2 is a fragmentary illustration of a portion of the toy which is typical of the whole as it appears.

Figure 3 is an elevation, partly in section, showing one of the detents with the switch mechanism controlled by the detent and actuated when the detent is moved by contact with the train. It also shows the signal and the magnet or solenoid which 80 actuates the signal and the detent moving the latter into the path of the train, this mechanism being incident to each unit. 85

Figure 4 is a section on the line 4—4 of Figure 3. 90

Figure 5 is a sectional plan showing the mechanism which is incident to each unit to be directly controlled by the player at that unit and which when so controlled makes and breaks the circuit including the magnet 95 in Figure 3, energizing the magnet at intervals.

Figure 6 is a sectional elevation of the same.

Figure 7 is a view of the top of the signal 100 tower.

Referring to the drawings by numerals:

the game, as illustrated, consists of an endless track, 1, which, as illustrated, includes four rails, 2, 3, 4 and 5, a suitable source of electricity, 6, which is preferably a battery or transformer, a train of cars or an electrically driven vehicle, 8, to run on the track and a plurality of player units, which may be duplicates or substantial duplicates of each other, one of said units being indicated by reference character, 7. Each of said player units preferably includes a switch control, 9, which, in the form of the invention shown, is a combined mechanical and electrical device which controls switch mechanism, 10, including a switch in the train actuating circuit, moving a portion of said switch mechanism 10, at intervals into the path of the train so that the train, if it passes the switch during such an interval, actuates the switch, breaking the train circuit and stopping the train. The switch control, 9, preferably comprises in each instance a manually operable member, 11, shown in the form of a crank, by which the switch control is actuated.

Each unit, as illustrated has a way-station, 12, which may be provided with a light, 13, which furnishes permanent illumination, the same being directly connected across the rails, 3, 4,—4 being the lighting circuit and 3 the return wire. Each station is also provided, in the form of the invention illustrated, and preferably, with extra illumination in the form of lights, 15, also connected across the lighting circuit rails, 3, 4, by connections, 16, but said connections, 16, also include spaced terminals or switch terminals, 17, adapted to be connected by suitable contact members, 18, carried by the switch mechanism, 10, so that the extra illumination is provided at each station only when the train circuit is broken by turning of the switch at that particular station which serves to stop the train at the station, as hereinafter described.

The illustration also includes a signal tower, 90, for each unit, with mechanical actuating means, 91, and colored glasses, 19, hereinafter described, for changing the color of the signal when the detent, 59, of switch mechanism, 10, is thrown into operative position in the path of the train.

The switch control, 9, as illustrated in detail in Figures 5 and 6, may include a crank, 11, on a shaft, 20, carrying a small pinion, 21, which meshes with a toothed idler, 22, carrying a pinion, 23, which meshes with another toothed gear, 24, which carries a pin, 25. The pin engages a balanced lever, 26, which is pivoted at 27, and provided with a counter-weight, 28, beyond the pivot. The arm of the lever on the opposite side of the pivot from the counter-weight engages an adjustable stop, 29, which permits it to rest in the path of the pin. It

also carries a depending scoop, 30, which is perforated or cut away at 31, as shown, so that it is adapted to receive liquid pumped into it as hereinafter described, which is almost immediately released. The liquid, by impact and weight, serves to overcome the counter-balance which normally lifts the lever out of contact with the pin, 25, and out of the path of the pin, serving to hold the lever in the path of the pin.

The crank shaft, 20, carries a toothed gear, 32, which meshes with a gear, 33, on the shaft of a pump, 34. This pump has its intake, 35, connected to a receptacle, 36, for liquid which extends around and beneath the scoop, 30, and the pump delivery pipe, 37, empties into the scoop, 30, providing the means for overcoming the counter-balance, 28, when the crank is rotated at a certain pre-determined speed, bringing the lever, 26, as aforesaid, into the path of the pin, 25. The switch control also includes electrical connections, 38, 39, forming part of a circuit, 40, which includes the electro-magnet or solenoid, 41, the same being likewise connected to the source of electricity, 6, also including a switch, 42, by means of which the solenoid may be disconnected. The circuit, 40, including the solenoid which is led into the control box by connections, 38, 39, which includes lever, 26, and pin, 25, is made and broken by means of the lever, 26, and the pin, 25. As shown, the connection, 39, is led to the counter-weight, 28, on the lever, 26, and the connection, 38, is led to a brush or suitable contact member, 43, which wipes the surface of the gear, 24, which carries the pin, 25, the mechanism being suitably insulated to prevent short-circuiting, which insulating features are obvious and not part of the invention.

In Figure 3, I have illustrated the electro-magnet or solenoid, 41, and the mechanism actuated thereby, including the switch mechanism, 10. The electro-magnet or solenoid, 41, is provided with a core, 50, which I have shown depressed to the position which it normally occupies. In Figure 3 I have shown a crossarm, 52, secured to the core and extending both to the right and left of the solenoid, being provided at each end with a collar, 53, 54, on the shafts, 55, 56, respectively. Each shaft is provided with an abutment, 57, 58, above the collar, which serves to lift the shaft when the collar is raised. The shaft, 56, carries at its upper end detent, 59, which is raised into the path of the train by the action of the solenoid lifting the core and the cross-arm, 52 and sliding the shaft, 56, upward, it being understood that the shaft, 56, passes through a hollow shaft, 60, to which it is keyed or non-rotatedly connected by a slot, 61 and a pin, 62, which permits it to slide relatively to the hollow shaft but not to turn. The hol-

low shaft, 60, carries a switch drum, 63, having contacts, 18, adapted to engage the terminals 17—17, in the extra lighting circuit and contacts, 65, adapted to engage the terminals, 64—64, in the train circuit, which consists in the main of the positive contact rail, 2, and the negative contact rail 5, the current being led from the source terminal number 12, the numbering being intended to indicate the number of volts in the preferred system through the various switch members, 10, to the rail, 2, at "A". After passing through the train motor or locomotive motor the current is returned to the negative wire, 5, from which it passes to the wire, 3, by a cross connection, 66, from which it is led to the negative side of the battery or source 6, at 0. The operation of the switch is, of course, apparent. When the arm, 59, is raised into the path of the train, by the action of the solenoid, the contact of the train rotates the shaft, 56, and hence the hollow shaft, 60, which, in turn, rotates the switch drum or block, 63, throwing the contacts, 18, into engagement with the terminals, 17, and throwing the contacts, 65, out of engagement with the terminals, 64, in the train circuit so that the train circuit is broken. Figure 4 has been described as a plan of the bottom portion of the mechanism shown in Figure 3. Having particular reference to this figure, it will be noted that the switch drum, 63, carries a lock plate, 70, having flat sides, 71, 72, which bear against the frame at 73, being connected by a rounded portion, 74, concentric with the shaft, 56. This serves to position and lock the switch in the on and off positions of the train circuit and of the extra lighting circuit. This plate is controlled by a spiral spring, 75, connecting a pin, 76, on the plate and a stationary pin, 77, on the frame. The plate, 70, also carries a crank pin, 79, which co-operates with the connecting rod, 80, connected to a crank pin, 81, on a cam, 82, pivoted on the frame at 83. This cam co-operates with the lower end, 84, of the shaft, 55, of the signal actuating mechanism, 91. The end, 81, acts as a cam follower and the cam, 82, acting on this follower, serves to hold the shaft in raised position whenever and so long as the switch mechanism, 10, is in a position which causes the train circuit to be broken at this point, that is, so long as the train is stopped at any given station, the signal at that station is in a corresponding position, which, preferably, having reference now to the signal, 19, in Figure 2, causes the signal to show red as viewed by the player. The signal is also independently actuated by the magnet, 41, through the cross-arm, 52. This cross-arm causes the signal shaft to be raised and the signal to show red or any preferred color when the switch detent, 59, is raised into the path of the train but the nature of the controller mechanism, 9, is such that the train switch, 10, with the arm, 59, may be raised into the path of the train and lowered before the train comes in contact with the arm, 59, so that the train is not stopped, the object of this portion of the mechanism being to cause the signal to show red whenever the switch mechanism, 10, with the arm, 59, is in a position to stop the train.

It will be apparent that with a number of players, one in each unit operating cranks, 11, the position of the corresponding train switches, 10, with the arms, 59, will depend upon the exact speed with which the crank is rotated, for to raise the arm, 59, it is necessary to complete the circuit, 38, 43, 25, 26, 39, see figure six, and this can only be completed when the flow of the liquid from the pump is sufficient in its impact or weight in or on scoop, 30, from which it flows with considerable speed, to counter-balance the lever, 26, with its weight, 28 and also the closing of this circuit is dependent on the contact of the pin, 25, with the lever, 26, which only continues through a comparatively small arc of the rotation of the gear, 24, so that even though the player rotates the crank with exactly the right speed, his chances of success are limited by the extent of this arc of contact of the pin, 25, with the lever, 26. This arc is capable of adjustment, as aforesaid, by varying the position of the stop, 29, as indicated and described. Whenever this contact is completed the magnet, 41, is energized, raising the detent, 59, into the path of the train but its entrance, as aforesaid, into this path is intermittent and its stay necessarily limited, so that it is exceedingly difficult for any player to intercept the trains, to accomplish which it is necessary, as aforesaid, for the train to come in contact with the arm, 59, rotating the switch, 10, to a position in which the train circuit is broken at 64, 65. The action of the signals and lights, whereby extra light is produced, at the station at which the train has stopped, and the signal at that station is caused to be actuated to show red whenever the train is standing at the corresponding station and whenever the switch is set to stop it at that station, has been fully explained. To start the train when it has once been stopped in this manner, it is necessary to rotate the switch to closed position of the train circuit, overcoming the tension of the spring, 75. Regarding the double mechanism for actuating the signals, it will be apparent that the cross-arm, 52, only holds the signal at the red position so long as the solenoid or magnet circuit, 40, is closed and this is intermittent and dependent on the balance of the lever, 26 and the position of the gear, 24. This serves to throw the signal

- for the unit or the station to red position, whenever the switch mechanism, 10, is in a position to stop the train, provided the train reaches it before its position changes.
- 5 The lower mechanism including the cam, 82, holds the signal corresponding to any station in the red position whenever the train circuit is broken by the switch mechanism, 10, so as to stop the train at that station.
- 10 I have thus described specifically and in detail a game in the form of a miniature railroad embodying my invention, in order that the nature and the operation of the same may be clearly understood; however, 15 the specific terms herein are used descriptively rather than in a limiting sense, the scope of the invention being defined in the claims.
- 20 What I claim and desire to secure by Letters Patent is:
1. A game comprising a miniature electric railroad, a circuit for actuating the same, a plurality of player units, each of several of the respective player units including a 25 switch having an actuating member, a member adapted to be moved into the path of the train at a point on the railroad corresponding to each said player unit, the said switch being in the train actuating circuit and adapted to break the same and means 30 for actuating the said member including a manually controlled member, means actuated thereby for intermittently moving the said movable member into the path of the train.
  - 35 2. A game comprising a miniature electric railroad having a train actuating circuit, a switch in the said circuit having a member adapted to be moved into the path of the train, so that the train in passing actuates 40 the switch and breaks the circuit, means for moving the said member into the path of the train including an electromotive member, connections for actuating the same, a balanced member included in the said circuit 45 and a manually operatable member engaging the said balanced member at intervals to complete the circuit.
  - 50 3. A game comprising a miniature electric railroad having a train actuating circuit, a switch in the said circuit having a member adapted to be moved into the path of the train so that the train in passing actuates the switch and breaks the circuit, means for moving the said member into the path of the train including an electromotive member, 55 connections for actuating the same, a balanced member included in the said circuit and a manually operatable member engaging the said balanced member at intervals to 60 complete the circuit, the said balanced member having connected thereto a variable balance with means actuated by the manually operable means for controlling the effect of the said variable element.

4. A game including a miniature electric 65 railroad with a train circuit, a train, a plurality of player units each including a station, lights therefor and a circuit for energizing the lights, each player unit also including a train switch in the train circuit 70 with a movable member adapted to be moved intermittently into the path of the train to operate the switch by contact with the train, means for moving the said movable member into the path of the train including electro- 75 motive means, a circuit for energizing the same, manually controlled means for closing the said latter circuit intermittently and a switch in the lighting circuit operated simultaneously with the train switch to light 80 the lights in the corresponding station whenever the train switch is operated to break the train circuit.

5. A game including a miniature electric railroad with a train circuit, a train, a plurality of player units each including a station, lights therefor and a circuit for energizing the lights, each player unit also including a switch in the train circuit with a movable member adapted to be moved intermittently into the path of the train to operate the switch by contact with the train, 85 means for moving the said movable member into the path of the train including electro- 90 motive means, a circuit for energizing the same, manually controlled means for closing the said latter circuit intermittently, a signal corresponding to each said unit and means connected to the said train switch, actuating means for operating the said signal. 95

6. A game including a miniature electric railroad with a train circuit, a train, a plurality of player units each including a station, lights therefor and a circuit for energizing the lights, each player unit also including a switch in the train circuit with a movable member adapted to be moved intermittently into the path of the train to operate the switch by contact with the train, 100 means for moving the said movable member into the path of the train including electro- 105 motive means, a circuit for energizing the same, manually controlled means, including a balanced member with a variable balancing element dependent on the speed of the control mechanism, for closing the said latter circuit intermittently, a signal corresponding to each said unit and means connected to the said train switch, and actuating 110 means for operating the said signal. 115

7. In an electrically actuated toy, a source of electricity, a circuit including electromotive actuating means for the toy, a balanced lever for making and breaking the 125 circuit, manually operated pumping means, means carried by the lever in the path of the pumped material whereby the balance of the

lever is changed varying the time of making and breaking the circuit.

8. In an electrically actuated toy, a source of electricity, a circuit and electromotive actuating means in said circuit for operating the toy, a balanced lever and manually operated means co-operating therewith, for making and breaking the circuit, manually operated pumping means, means carried by the lever in the path of the pumped material

whereby the balance of the lever is changed varying the time of making and breaking the circuit.

Signed by me at Baltimore, Maryland, this 31st day of December, 1920.
